UNITED STATES PATENT OFFICE.

SARAH SOPHIA FREEMAN, OF LINCOLN, NEBRASKA.

DRESSMAKER'S RULER.

SPECIFICATION forming part of Letters Patent No. 722,221, dated March 10, 1903.

Application filed October 14, 1902. Serial No. 127,301. (No model.)

To all whom it may concern:

Be it known that I, SARAH SOPHIA FREEMAN, a citizen of the United States, residing at Lincoln, in the county of Lancaster and 5 State of Nebraska, have invented a new and useful Dressmaker's Ruler, of which the following is a specification.

The invention relates to a dressmaker's ruler.

10 The object of the present invention is to embody in one device a series of universal curves which will include all the curves of the human form and which will afford all that is required to outline any design or pattern for 15 cutting any garment to fit the individual form of any size.

The invention consists in the construction and novel combination and arrangement of parts hereinafter fully described, illustrated 20 in the accompanying drawings, and pointed out in the claim hereto appended.

In the drawings, Figure 1 is a plan view of 25 the dressmaker's ruler constructed in accordance with this invention. Fig. 2 is an edge view.

Like numerals of reference designate corresponding parts in both figures of the drawings.

1 Designates a dressmaker's ruler curved 30 longitudinally and widened near the center at 2. From the widest point of the ruler the side lines 2 and 3 extend in differential curves, slowly converging toward the end 4 of the ruler, each curve having a multiple of radii 35 and the radii of both curves being located on the same side of the ruler. The curved line 2 presents a convex edge, and the opposite side line 3 presents a concave edge. The ruler also tapers from the widest point toward its other 40 end 5, one side, 6, being formed in a curve and the other side, 7, being straight. Starting from the widest portion of the ruler and extending toward the end 4 is a curved slot 8, having side lines or edges 9 and 10, formed 45 in differential curves starting from one end 11 of the slot and diverging on short radii for a distance and then slowly converging in differential curves to a common point 12 at the other end of the slot. At the opposite half or 50 portion of the ruler is located a curved slot or opening 13, forming side lines or edges 14 and

15, starting from a common point 16 near one end of the ruler and slowly diverging toward the center of the same, where they are connected by a curved edge 17. The straight 55 edge 7 at this portion of the ruler is provided with a series of graduations 18, which form a measuring-scale.

After a pattern has been drafted in straight lines in accordance with the measurements 60 taken the ruler is employed for constructing the actual lines. The curved edge 2 is used for shaping the back, and the opposite edge 3 is employed for shaping the side portions of the back. The edge 6 forms a dart-curve and 65 15 is used for shaping the darts of the front of the waist. The edge 10 forms an arm-curve and is used for shaping the armhole of the front and back. The lower portion of the curve 9 is used for shaping the neck, and the 70 upper portion of the curve 9 is for shaping the shoulder, while the entire edge or curve 9 is also employed for shaping the tops of sleeves. The scale 18 is employed for measuring the patterns in laying off the same for obtaining the 75 proper proportions. The lower inner edge or curve 14 is a skirt-curve for shaping gores and giving flares at the bottom of skirts and for drawing skirt-darts. It is also used for shaping the bottom edge of skirts and for shaping 80 collars, revers, lapels, pockets, and trimmings. The curve 15 is a sleeve-curve and is used for shaping the sleeve-seams.

What I claim is—

A device of the class described consisting 85 of an oppositely-tapered longitudinally-curved ruler provided at one side with a straight graduated edge and having oppositely-disposed curved slots, one of the slots having inwardly-diverging curved side edges 90 and a connecting curved edge at the inner end of the slot and the other slot having converging end portions, substantially as described.

In testimony that I claim the foregoing as 95 my own I have hereto affixed my signature in the presence of two witnesses.

SARAH SOPHIA FREEMAN.
